UNITED STATES PATENT OFFICE.

WILBUR F. GARRETT, OF CENTREVILLE, IOWA.

PENCIL-SHARPENER.

SPECIFICATION forming part of Letters Patent No. 597,643, dated January 18, 1898.

Application filed November 21, 1896. Serial No. 613,036. (No model.)

To all whom it may concern:

Be it known that I, WILBUR F. GARRETT, a citizen of the United States, residing at Centreville, in the county of Appanoose and State 5 of Iowa, have invented certain new and useful Improvements in Pencil-Sharpener; and I do hereby declare the following to be a full, clear, and exact description of the invention, such as will enable others skilled in the art to 10 which it appertains to make and use the same.

This invention relates to pencil-sharpener, and has for its object to provide a simple, neat, and efficient sharpener for pencils which is adapted to be used in connection with any 15 ordinary pencil and to remain at all times thereon, said sharpener serving, in addition to its usual function, as a protector for guarding the point of the pencil and preventing the point thereof from becoming broken.

20 With these and other objects in view the invention consists in certain novel features and details of construction, as hereinafter fully described, illustrated in the drawings, and pointed out in the claim.

25 In the accompanying drawings, Figure 1 is a perspective view of the improved pencil-sharpener. Fig. 2 is a longitudinal section through the same. Fig. 3 is a similar section showing the improved sharpener engaging 30 the point of a pencil as when sharpening the same. Fig. 4 is a similar view showing the sharpener moved upward for protecting the point of the pencil.

Similar numerals designate corresponding 35 parts in the several figures of the drawings.

The improved pencil-sharpener contemplated in this invention is preferably formed in one piece from a single blank of sheet-steel or other suitable metal having the requisite 40 degree of hardness, and this blank, which is in the form of a strip 1, is coiled spirally into the form of a volute spring, with the exception that the coils lie in the same plane, the device resembling a pointed cone with a spiral groove extending from apex to base.

The several coils which compose the device are sharpened at their front edges, so as to engage with the point of the pencil as the latter is turned therein or as the device is turned 50 around the pencil for the purpose of removing the wood and gradually shaving the pen-

cil down to a nicely-tapered point. The extremity of the blank at the pointed end of the sharpener is also beveled, as indicated at 2, to form a cutting-lip, which coöperates with the lead point of the pencil for trimming down and sharpening said point when the pencil is revolved in a reverse direction, thereby enabling the lead to be sharpened without trimming down the wood any further. The 60 strip 1 at its rear end is provided upon opposite sides, one or both, with inwardly-extending feeding-spurs 3, inclined slightly to the axis of rotation, and when the sharpener and pencil are given a relative rotation these spurs 65 indent the wood of the pencil and form threads therein, thereby operating to feed the sharpener inwardly on the pencil simultaneously with the shaving down of the point thereof.

The sharpener is intended to remain at all times on the pencil, and it may be given a slight movement or a complete turn occasionally for keeping the pencil properly sharpened. When the pencil is not in use, the sharpener may be turned reversely thereon, 70 whereupon the spurs 3 will travel in the threads which they have previously formed, thus carrying the sharpener outward on the point of the pencil in such manner as to cover the pencil-point, thereby protecting the same 75 and preventing breakage thereof when the pencil is carried in the pocket.

Where the sharpener is made out of very thin material, the rear portion of the strip 1 may be provided with a longitudinally-projecting lip 4, which is riveted to the adjacent coil of the device, thus imparting strength thereto. It is also advisable to provide said strip at its rear end with a laterally and upwardly projecting lip 5, forming a finger-hold 80 for giving the required purchase while rotating the device upon the pencil.

It will be seen that the device is extremely simple in construction, that it may be manufactured at very slight cost, and that in addition to sharpening a pencil it also serves as a point-protector, and is also in the nature of an ornamentation for the pencil.

Having thus described my invention, what is claimed as new is—

100 A pencil-sharpener, comprising a strip of metal coiled in volute form and sharpened as

to one of its edges, the extremity of said strip at the end of the smallest coil being also sharpened to form a cutting-lip for acting on the point of the pencil when the direction of rotation of the sharpener is reversed, the rear end of the strip being deflected radially outward, a longitudinal extension at the rear portion of the strip extending forward and united to the adjacent coil, and one or more oblique 5 feeding-spurs projecting inward from the

sharpener, substantially as and for the purpose described.

In testimony whereof I have signed this specification in the presence of two subscribing witnesses.

WILBUR F. GARRETT.
